UNITED STATES PATENT OFFICE.

OSCAR BOTO SCHILLBERG, OF NEW YORK, N. Y.

PROCTOTHERAPY APPARATUS.

Application filed February 20, 1928. Serial No. 255,553.

This invention relates to improvements in a proctotherapy apparatus for the irrigation of the colon and the like.

Among the salient objects which the present invention has in view are: To render the apparatus more convenient of manipulation; to mount the parts containing the medicinal preparations for free and universal movement to facilitate the handling thereof; to improve the means for regulating the temperature of the medicinal preparation; to provide for escape of the gases formed in the containers for the medicinal preparations evolved by virtue of the temperatures thereof; and in general to improve and render more efficient the proctotherapy apparatus.

In the drawings:

Figure 1 is a front elevational view of a portion of an apparatus constructed in accordance with this invention in showing the parts in one position;

Figure 2 is a plan view with the parts in positions corresponding to the positions of Figure 1;

Figure 3 is an end elevational view looking at the right of Figure 1 and showing a fragment of the construction;

Figure 4 is a front elevational view of the apparatus with the parts in a different position;

Figure 5 is a plan view of the apparatus, showing in full lines the parts in positions corresponding to the positions of Figure 4 and in dotted lines positions which the parts are adapted to assume in service;

Figure 6 is a view on an enlarged scale of a fragment of the construction, partly in elevation and partly in section;

Figure 7 is a plan view, partly sectional and broken away of one of the parts of the apparatus;

Figure 8 is an elevational view, partly sectional, partly broken away, of the part shown in Figure 7;

Figure 9 is an enlarged view, partly in elevation and partly sectional and broken away showing a detail of construction and a feature of the invention;

Figure 10 is an enlarged elevational view, partly sectional and partly broken away, of a container for a medicinal preparation illustrating means for raising the temperature thereof and the means for permitting the escape of gases evolved by vaporization of the preparation;

Figure 11 is a side elevational view of the

container disposed in service, partly schematic to better illustrate the invention;

Figure 12 is a plan view of Figure 10 illustrating the means for permitting escape of the evolved gases in the container.

Referring now more particularly to the drawings, the invention is illustrated as applied to a proctotherapy apparatus comprising the customary table 20 in which the patient is reclined, having a drainage means 21 (see Figs. 4 and 5) for the medicinal fluids after application. The table embodies a plurality of legs 22 arranged in any preferred or desired fashion, and preferably of metallic tubular nature, as of pipes or the like. The various containers having medicinal fluids, or preparations, or other liquids used in irrigating the patient are supported on one of the legs or other vertical member of the table, and to this end a bracket 23 of any preferred or desired form is mounted on one of the legs or other vertical member—preferably at the end of the table and approximately midway between the sides thereof—in a pivotal manner so as to be swung through an arc of approximately 180° and positioned in any desired place in its arcuate path.

On the end of the bracket 23, the various containers for the medicinal preparations or other liquids are supported. In the drawings there are three containers shown, a large center container 24 and two small end side containers 25 and 26. The center container 24 is supported on a horizontal support 27 extending between and mounted on vertical rods 28 and 29 positioned in spaced parallel relation. These rods, 28 and 29, are in turn supported on another horizontal member 30 which is centrally supported on the end of the bracket 23 and in a pivotal manner by means such as a rivet or bolt 31, which permits the horizontal member 30 and parts carried thereby to be rotated as a unit with it as an axis. The containers 25 and 26 are in turn pivotally supported on rods 28 and 29 as shown at 32 and 33 respectively and may in turn rotate around said rods as axes. The containers, as pointed out above, contain the various medicinal liquids for application in irrigation and cleaning, and the liquids may be applied to the patient through tubes 34 (see Figs. 1 and 2), in the manner already well known. As stated the liquids after application are carried away through drain 21. By virtue of the above arrangement the containers for the fluids may be adjusted with

nicety in an universal manner within, of course, a limited area, at the end of the table. The containers are mounted so as to be swung around axis 31 as the axis of rotation, and this axis is in turn adapted to be moved through an arc of 180° with a radius corresponding to the effective length of the bracket 23. In addition the containers 25 and 26 are adapted to be rotated around rods 28 and 29 as axes and thus all the containers may be positioned with nicety for convenience of the person administering to the patient. The end containers 25 and 26 may also be vertically adjusted on the rods 28 and 29, if desired, to vary the height of the containers and the pressure behind the liquids administered.

In Figures 7 to 11 inclusive, the preferred construction of each end container is illustrated. By reference to these figures, it will be seen that the container comprises a body portion 35 for the accommodation of the medicinal fluid and a cover 36 for the body portion. The cover has associated therewith an electric socket 37 which is preferably positioned at the center of the cover and is supported on the cover by a flange 38 or the like. This flange is attached to the cover in any convenient fashion as by means of screws or other fastening members 39 extending through lugs 40 (see Fig. 12) of the flange into the cover. The flange also has a number of openings 41 establishing communication between its interior and the atmosphere and arranged in a general circular manner in the flange. The portion of the cover beneath the flange is also provided with openings 42 through which vapors or gases within the container may escape into the interior of the flange and thence through the openings 41 thereof to the atmosphere. Thus, the vapors generated within the container by application of heat to the medicinal fluid are provided with an escape and no pressure may be built up within the container due to such vapors or gases.

The temperature of the medicinal preparation within the container is controlled by an electric heating unit which comprises an elongated electric bulb 43 which is screw-threaded into an elongated supporting member 44 which in turn is threaded within the socket 37, current being supplied to said bulb from said socket through the member 44. The elongated bulb is thus positioned near the center of the container and is such as to impart a

uniform temperature throughout the entire body of the medicinal fluid.

I preferably provide means for preventing corrosion of the plug portion of the bulb 43 and the center of member 44 by the medicinal fluid and to this end I preferably employ an elastic ring 45 of rubber or other material, which is clamped by the bulb against the end of member 44, as shown in Figure 9, when the bulb 43 is secured therein. This ring member is preferably positioned in a recess 46 at the end of the member 44 and a cap 47 is also disposed over the end of the member 44. The ring in addition to serving the function above outlined may also act to maintain the bulb 43 securely in its socket.

The covers 36 of the various containers may also have funnels 48 with pivoted covers for convenient opening and closing and the medicinal fluids may be added to the containers from time to time through the funnels as necessity arises. The thermometer 50 may also be inserted in a container and supported therein as from a hook 51 on the inside of the cover and will indicate the temperature of the fluid within the container.

Claims:

1. In proctotherapy apparatus, the combination with a table, of a bracket swivelly mounted at one corner thereof, a frame swivelly mounted at the free end of said bracket including spaced vertically extending parallel guide rods, a plate connecting the free ends of said rods, a container supported by said plate between said rods, a pair of rotatable bracket arms supported for vertical adjustment on said rods, and containers supported at the outer ends of said arms.

2. The combination as set forth in claim 1, said containers being adapted to receive medicinal preparations, and means in said containers for heating the preparations contained therein.

3. The combination as set forth in claim 1, said containers being adapted to receive medicinal preparations, means for heating the preparations, and automatic venting means for the containers.

4. The combination as set forth in claim 1, said containers being adapted to receive medicinal preparations, means for heating the preparations, venting means for the containers, and means through which the preparations may be discharged.

OSCAR BOTO SCHELLBERG.
